Application August 9, 1954, Serial No. 448,538

12 Claims. (Cl. 340—172)

This invention relates generally to electrical apparatus in which the energization of a plurality of load devices at an operating station is controlled by the selective manipulation of elements disposed at a remotely located control station and in which the number of conductors required to be extended between the stations is less than the number of load devices to be operated. More particularly, the invention relates to apparatus of the above character in which a control voltage at the operating station varies in accordance with changes in the value of resistance effective across the conductors at the operating station ends thereof as determined by manipulations of the control elements at the control station and in which such control voltage is applied to a mechanism operable to energize the respective load devices individually in response to different predetermined values of the control voltage.

One object of the invention is to provide, in apparatus of the above character, novel voltage responsive mechanism which is simpler in construction and operation and requires fewer parts than similar prior art mechanism.

Another object is to provide novel voltage responsive mechanism in which energization of the respective load devices is controlled by a corresponding number of electron tubes and in which the grid bias circuits of the latter are composed of elements of fixed characteristics and are arranged in a novel manner such that different predetermined values of the control voltage are utilized to condition the respective tubes for conduction individually and, at the same time, to maintain all of the tubes other than the selected one in a cut-off condition.

A more detailed object is to arrange the bias control circuits of a plurality of double grid load control tubes in a novel manner for application of the control voltage to both grids of all of the tubes simultaneously to condition a different tube for conduction while maintaining the other tubes cut off in response to each predetermined value of the control voltage.

The invention also resides in the novel arrangements of the load devices and tubes at the operating station to insure that a single load device is energized in response to the simultaneous manipulation of more than one control element.

Other objects and advantages of the invention will become apparent from the following detailed description taken in connection with the accompanying drawings, in which—

Figure 1 is a schematic view and wiring diagram of control apparatus embodying the novel features of the present invention.

Fig. 2 is a chart showing the bias voltage on the grids of the control tubes under different operating conditions.

In the drawings, the invention is shown for purposes of illustration embodied in electrical apparatus for controlling the selective energization of a plurality of load devices L1, L2, L3, L4, L5, L6, L7 and L8 at an operating station 10 in response to manipulation of control switches S2, S3, S4, S5, S6, S7, and S8 at a remotely located sta-

tion 11. The improved apparatus is of the type in which the switches cooperate with a plurality of resistors R2, R3, R4, R5, R6, R7, and R8 at the control station to change the value of the resistance effective across conductors 12 and 13, herein two, fewer in number than the load devices, extending between the stations. At the operating station, a resistance element 14 is connected in series with a constant voltage direct current source 15 across the conductors 12 and 13 so that variations in the effective resistance across the latter produce corresponding changes in the current flow through the resistance element and in the value of the voltage across the latter. This voltage is a control voltage and is applied to a voltage responsive mechanism 16 which is operable to energize the load devices individually in response to different predetermined values of the control voltage.

The present invention contemplates the provision in apparatus of the above character, of a novel voltage responsive mechanism 16 which, as compared to similar prior art apparatus, requires fewer parts and is simpler in construction and operation. Generally, the improved voltage responsive mechanism comprises a sensing section 17 responsive to the control voltage across the resistance element 14 and having different predetermined output voltage conditions corresponding to the respective predetermined control voltage values. Such output voltage conditions are sensed by a series of load control elements T1, T2, T3, T4, T5, T6, T7, and T8 which correspond in number to the load devices and are operable respectively in response to the different predetermined voltage conditions to energize the corresponding load devices individually. In this instance, the load control elements are electron tubes of the type having two control electrodes or grids both controlling conduction by the tube and operable to render the tube non-conductive when either grid is biased negatively with respect to the cathode. The sensing section 17, where such tubes constitute the load control elements, comprises bias control circuits by which the control voltage is applied to both grids of all of the tubes simultaneously to condition a different tube for conduction while maintaining the other tubes cut off in response to each predetermined value of the control voltage. With this arrangement, the different predetermined output voltage conditions of the sensing section referred to above are different bias voltage values which are applied to the grids of the control tubes and which change in accordance with variations in the control voltage to condition the tubes for conduction individually.

Each of the load tubes comprises output electrodes, a plate P and a cathode C, and the two grids G and G' and is conditioned for conduction when the potential of both grids is substantially zero or of a positive value. To utilize the control voltage of the resistance element 14 to change the potential of both grids of all of the load control tubes simultaneously, the resistance element is coupled to each of two bias control circuits. One of the latter is connected to one grid G of each tube and is operable to apply potentials of progressively increasing magnitudes to the different grids. The other circuit is connected to the other grid G' of each tube and is operable to apply to the different grids potentials which correspond to the potentials of the first circuit but decrease progressively in magnitude. The resistance element 14 is coupled between such circuits and a conductor 18 common to the cathodes C of all of the tubes so that changes in the voltage of the resistance element are applied in opposite directions to the two bias circuits and are added algebraically to the potentials of the latter for bringing the potentials of both grids of a selected one of the tubes approximately to zero while maintaining a cut-off potential on one grid of all of the other tubes.

Herein, each of the load tubes is a thyratron of the 2D21 type in which the cut-off condition depends on the bias applied to both the shield grid G' and the control grid G . For example, when the voltage in the plate circuit of such a tube is 150 volts alternating current of 60 cycles per second, the tube is cut-off by a negative bias voltage of 2 volts on the shield grid G' when the control grid bias is a positive 4 volts or by a negative bias voltage of 4 volts on the control grid G when the shield grid potential is a positive 8 volts. Curves of such cut-off voltages are available from the tube manufacturer, herein, Radio Corporation of America of Harrison, New Jersey.

In the present instance, the first bias circuit comprises a voltage divider formed by a plurality of resistors r_1 , r_2 , r_3 , r_4 , r_5 , r_6 , and r_7 connected in series with a resistor r_9 across a suitable constant voltage direct current source 20 , the positive terminal of the latter being connected through the resistor r_9 and a conductor 21 to the first divider, r_1 and the negative terminal being connected by a conductor 22 to the last divider resistor r_7 . The divider resistors are connected between adjacent ones of the control grids G of the series of load tubes or, stated another way, the respective grids G are connected to successive taps of the divider or to corresponding terminals of the divider resistors. For example, the first divider resistor r_1 is connected between the grid G_1 of the first tube T , and the grid G_2 of the second tube T_2 , the grids G_1 and G_2 being connected to the last two taps at one end of the divider. Herein, the voltage of the source 20 is 75 volts and the values of the divider resistors and the series resistor r_9 respectively are 500 ohms each and 5900 ohms so that the voltage drop across each divider resistor is approximately 4 volts and the total drop across the divider from the first grid G_1 to the last grid G_8 is a negative 28 volts.

The second bias circuit comprises a similar divider having resistors r_1' , r_2' , r_3' , r_4' , r_5' , r_6' , and r_7' connected respectively between adjacent ones of the other grids G' of the load tubes and in series with a resistor r_9 across a suitable constant voltage direct current source 24 . The positive terminal of the latter is connected through the resistor r_9 and a conductor 24 to the last divider resistor r_7' and the negative terminal is connected by a conductor 25 to the first resistor r_1' . The values of the source voltage and of the divider resistors are the same as in the first bias circuit, but the value of the series resistor r_9 equals 1200 ohms so that the voltage drop across each divider resistor is approximately 8 volts positive with the potential of the last grid G_8' equal to 56 volts positive when the grid G_1' of the first tube is negative. A resistor 26 of suitable value, for example, 2 million ohms, is connected in series with each grid to limit current flow therethrough.

To complete a bias circuit between each of the grids G and G' and the cathode C of each tube T , opposite ends of the resistance element 14 are connected respectively to the conductors 21 and 25 and through the latter to the first resistors r_1 and r_1' of the voltage dividers and an intermediate tap of the resistance element is connected through ground to the common cathode conductor 18 . The resistance element 14 thus is divided into two sections $14a$ and $14b$, the former being common to the grid-cathode circuit of each of the grids G of the tubes and the latter being common to the grid-cathode circuit of each of the grids G' of the tubes. For example, the bias circuit of the grid G_3 of the tube T_3 extends from the cathode C_3 to the grid through the cathode conductor 18 , ground, the first resistance section $14a$, the conductor 21 and the first divider resistor r_1 and r_2 . The bias circuit of the grid G_3' of the tube T_3 correspondingly extends through the cathode conductor 18 , ground, the second resistance section $14b$, the conductor 25 , and the second divider resistors r_1' and r_2' . In each of these circuits, the potential of the effective section of the re-

10 resistance element 14 is added algebraically to the potentials of the effective divider resistors to determine the potential of the grid with respect to the cathode.

15 The polarity of the source 15 connected to the resistance element is such that the potential of each of the sections $14a$ and $14b$ of the latter is opposed to that of the divider resistors in circuit with the section. Herein, the resistance of the first section $14a$ equals 1600 ohms and that of the second section $14b$ equals 3200 ohms so that the voltage drop across the latter is double that across the first section for a given current flow through the sections. The potential of the source 15 is 105 volts and the negative and positive terminals of the source are connected respectively to the second resistor section $14b$ and through the control station conductors 12 and 13 to the first resistor section $14a$.

20 When an open circuit exists across the conductors 12 and 13 at the control station, no current flows through the grid control resistance element 14 and the only potentials applied between the respective grids and their corresponding cathodes are those applied by the voltage divider resistors. Under these conditions, as shown in the first line of the table in Fig. 2, the potential of each of the grids G_1 and G_1' with respect to the cathode C_1 25 is zero and the tube T_1 thereby is conditioned for conduction when its plate or output circuit is closed. In the case of all of the other tubes, a potential of at least 4 volts negative is applied to one of the grids of each of the tubes to maintain the latter in cut-off condition. 30 Since the tube T_1 is conditioned for conduction when the conductors 12 and 13 are open-circuited, no switch is provided at the control station for this tube. Conduction by each of the other tubes T_2 to T_8 is controlled by the respective switches S_2 to S_8 each of which is operable 35 when closed to connect across the conductors 12 and 13 resistance of the proper value to provide the correct voltage drop across the resistance element 14 for bringing the potential of each of the grids of the corresponding tube substantially to zero and thereby conditioning the tube for conduction.

40 The resistors R_2 , R_3 , R_4 , R_5 , R_6 , R_7 , and R_8 and the switches S_2 , S_3 , S_4 , S_5 , S_6 , S_7 , and S_8 of the control station 11 also are arranged in a novel manner to insure that only one of the load tubes is conditioned for conduction even though two or more of the switches may be closed simultaneously. Such arrangement comprises connection of all of the resistors in series with one conductor 12 and location of the switches in individual short circuits corresponding in number to the resistors and extending between corresponding ends of the latter and the other conductor 13 . Thus, when any switch such as the switch S_7 is closed, the resistors R_7 and R_8 located between the switch and the first conductor 12 are connected across the conductors and the remaining resistors R_2 , R_3 , R_4 , R_5 , and R_6 are short circuited so that closure of any of the switches S_2 , S_3 , S_4 , S_5 , and S_6 associated with such remaining resistors does not change the value of resistance across the conductors. In the present instance, the switches S_3 , S_4 , S_5 , S_6 , S_7 , and S_8 are of the 45 momentary contact push-button type which are spring urged into open positions. For a purpose to appear later, the switch S_2 is of the single pole single throw type. The values of the resistors R_2 to R_8 , in this instance, are 21,000 ohms, 7000 ohms, 3500 ohms, 2100 ohms, 1400 ohms, 1000 ohms, and 1200 ohms respectively.

50 Each of the load devices L_1 to L_8 , which herein are relays, is arranged to be energized in response to conduction by the corresponding one of the load tubes T_1 to T_8 . For this purpose, the coil of the relay is connected in series with the plate P in the plate or output circuit of the corresponding tube. Such output circuit is completed by connection of the relay coil through an individual conductor 27 to a conductor 28 which is common to the plate circuits of all of the load tubes and is connected to a suitable alternating current power supply 29 .

connected to the common cathode conductor 18 through ground. Herein, the potential of this source is 150 volts. With such an alternating source in the plate circuit of each load tube, the latter conducts only in positive half cycles and is rendered nonconductive in the first negative half cycle after a cut-off potential is applied to one of its grids. To avoid energization of each load relay in the event that the associated tube is rendered conductive for only a few cycles of the source 29 in response to transient currents in the grid circuits, the relays preferably are of the time delay type well known in the art and requiring current flow therethrough for a longer period such as ten cycles before pulling in.

It will be seen from the foregoing that each load tube conducts to energize the associated load relay when the plate circuit of the tube is completed and the potential of each grid of the tube is substantially zero. To avoid conduction of more than one tube and energization of the associated load devices simultaneously, contacts of the load relays L1 to L8 and the output circuits of the tubes are arranged in a novel manner such that the output circuits of all of the tubes disposed between a terminal one of the tubes and all tubes between the terminal tube and any of the tubes which is conducting are disabled or interrupted upon energization of the relay associated with the conducting tube. Such operation is accomplished by connecting the common plate conductor 28 directly to the conductor 27 of the last load relay L8 and by including, in the output circuit of each tube starting with the first tube T1 and between the load relay coil thereof and the common plate conductor, normally closed contacts of each of the load relays of all of the tubes up to the last tube T8. In the present instance, a pair of normally closed contacts of each load relay starting with the last relay L8 is connected between the conductor 27 of the latter and the adjacent relay coil conductor 27 so as to be included in series in the output circuits of all of the tubes disposed between the corresponding tube and the first tube T1. Thus, the output circuit of the fourth tube T4, for example, includes in series in its output circuit the normally closed contacts L51, L61, L71 and L81 of the respective relays L5, L6, L7, and L8 so that, when any one of the latter is energized, the fourth tube is disabled.

In the use of a control of the above character, other contacts such as the contacts L12 to L82 of the respective relays L1 to L8 may be utilized in suitable control circuits to perform different functions upon energization of the relays. It is sometimes desirable to use two of the load relays to control the same condition, for example, direction of rotation of a spindle in a machine tool, and to maintain the condition as established by energization of either relay even after the latter is deenergized. This is accomplished in the present instance by the provision of a control relay AR whose coil is connected in series with normally open contacts L11 of the first load relay L1 and normally closed contacts L22' of the second relay L2 across a suitable voltage source 33 so that the control relay circuit is closed and opened respectively upon energization of the first relay L1 or the second relay L2. The relay AR includes normally open contacts AR1 which are connected in a shunt around the first relay contacts L11 to complete a holding circuit for the control relay when the first relay is deenergized. To avoid continued energization of either load relay while the condition to be established by its energization is already prevailing, normally closed contacts AR2 and normally open contacts AR3 of the control relay are connected in series respectively with the first load relay coil and the second load relay coil. The switch S2 controlling the second load relay L2 is a single pole single throw switch to enable the operator at the control station to leave the switch actuator in one position or the other and thereby determine by observation what condition of the control relay prevails. The condition such as direction of spindle rotation which is controlled in accordance

with energization and deenergization of the control relay AR may be changed in response to opening and closing of another set of contacts (not shown) of this relay.

In the operation of the improved control apparatus described above, let it be assumed that power is available at the various voltage sources and that all of the switches S2 to S8 are open. Referring to Fig. 2, it will be seen that, under these conditions, the grids G1 and G1' of the first load tube T1 are both at zero potential so that the tube is conditioned for conduction. One of the grids of each of the other tubes T2 to T8 is at a negative potential of at least 4 volts and the other tubes are thereby maintained in cut-off condition so that the normally closed contacts L21 to L81 in the output circuit of the first tube T1 are closed. With the control relay AR deenergized so that its contacts AR2 are closed, the plate circuit of the first tube is completed and the latter conducts for energization of the first load relay L1. The contacts L11 of this relay close to complete the energizing circuit of the control relay AR. Upon pull-in of the latter, the contacts AR3 thereof in the plate circuit of the second tube close to enable this tube to conduct when the switch S2 is closed, the contacts AR2 open to disable the first load tube output circuit, and the contacts AR1 close to complete the holding circuit of the control relay. The energized condition of the control relay prevails during closure of the other switches S3 to S8 and until the switch S2 is closed because the holding circuit for the control relay does not include any of the contacts L31 to L81 of the relays L3 to L8.

When the switch S2 is closed, all of the control station resistors R2 to R8 are connected in series across the conductors 12 and 13 to complete a circuit through the grid control resistance element 14 and the source 15 for producing a potential of 4 volts across the first section 14a in series with the resistors r1 to r7 of the first bias circuit, thereby raising the potential of each of the grids G1 to G7 by this amount. At the same time, a potential of 8 volts negative across the second section 14b of the resistance element is applied in series with the resistors r1' to r7' to lower the potentials of the grids G1' to G7' of the load tubes. As a result, the grids G2 and G2' of the second tube T2 are both at zero potential and the tube conducts to energize the corresponding relay L2 and open the circuit to the control relay AR at the contacts L22'. The control relay then is deenergized and the contacts AR2 thereof close in the plate circuit of the first tube T1 to enable the latter to conduct when the switch S2 is opened. Also, the contacts AR3 open in the plate circuit of the second tube to disable this tube. This condition of the control relay prevails during closure of any of the other switches S3 to S8 and until the switch S2 is opened.

Upon closure of any of the other switches S3 to S8, a proper voltage is applied across the resistance element 14 and in the respective bias control circuits to bring the potentials of both grids of the corresponding load tube substantially to zero for conduction by the tube and energization of the corresponding load relay in a manner similar to energization of the second load relay L2 upon closure of the switch S2. As soon as all of the switches are opened, a negative bias is restored to one grid of each of the tubes except the first tube T1 to maintain such tubes nonconductive. If two or more switches are closed simultaneously, only the corresponding tube nearest the power supply end of the series of tubes will conduct. Thus, closure of the switches S2 and S7 (see Fig. 2) corresponding to the second and seventh tubes T2 and T7 results in conduction only by the seventh tube T7 due to short-circuiting of all control station resistors except R7 and R8 and due to opening of the normally closed contacts L71 in the plate circuit of the second tube. Similarly, closure of the switches S4 and S7 for the fourth and seventh tubes T4 and T7 results in conduction only by the latter tube. If the last switch S8 is closed along

with the switch S7 for the seventh tube, then only the eighth tube T8 will conduct.

By virtue of the novel arrangement of the load tubes and the bias circuits described above, a single control voltage may be utilized not only to condition the tubes for conduction selectively, but also to maintain in a cut-off condition the other tubes which are not selected. Such arrangement also makes it possible to use only two conductors between the operating station and the control station and to locate at the latter only resistance elements and switches which are rugged and durable and whose characteristics remain fixed in service use. The size of the control station and the number of parts required to be located there thus are reduced and the portability of the station is increased. Due to the manner of connection of the switches S2 to S8 to the resistors R2 to R8 at the control station and of the normally closed contacts of the load relays into the output circuits of the load tubes T1 to T8, energization of two load relays simultaneously is avoided even though the operator may inadvertently close more than one of the switches at the same time.

I claim as my invention:

1. In control apparatus, the combination of, a plurality of control elements arranged in a sequence and each having an output circuit, a corresponding number of relays arranged in a similar sequence and respectively connected in the different output circuits of said control elements for energization of each relay when the corresponding control element is rendered effective, each of said relays having normally closed contacts in the output circuit of a preceding control element whereby energization of one of said control elements and its relay results in interruption of the output circuit of such preceding control element, selectively operable means for rendering said control elements effective individually, and a separate relay controlled by the terminal and adjacent ones of said relays at said one end of said sequence and having an energizing circuit including normally closed contacts of the adjacent relay and normally open contacts of the terminal relay for energization and deenergization of the separate relay in response to energization of the terminal relay and the adjacent relay respectively, said separate relay having normally open contacts connected in parallel with said normally open terminal relay contacts to provide a holding circuit for the separate relay and normally closed contacts and normally open contacts connected respectively in series with the coil of said terminal relay and the coil of said adjacent relay whereby to enable a condition established by selective energization of either of the terminal and adjacent relays to be maintained after deenergization of such relay as occurs upon energization of any of the relays located between each of the terminal and adjacent relays and the other end of said sequence.

2. In control apparatus, the combination of, a plurality of control elements arranged in a sequence and each having an output circuit, a corresponding number of relays arranged in a similar sequence and respectively connected in the different output circuits of said control elements for energization of each relay when the corresponding control element is rendered effective, each of said relays having normally closed contacts in the output circuit of a preceding control element whereby energization of one of said control elements and its relay results in interruption of the output circuit of such preceding control element, selectively operable means for rendering said control elements effective individually, and a separate relay controlled by the terminal and the adjacent ones of said relays at said one end of said sequence and having an energizing circuit including normally closed contacts of a first one of the adjacent and terminal relays and normally open contacts of the other of such relays for energization and deenergization of the separate relay in response respectively to energization of the

first relay and deenergization of the other relay, said separate relay having normally open contacts in parallel with said normally open contacts of said first relay whereby to enable a condition established by selective energization of either of the terminal and adjacent relays to be maintained after deenergization of such relay as occurs upon energization of any of the relays located between each of the terminal and adjacent relays and the other end of said sequence.

3. In control apparatus, the combination of, a power supply, a plurality of load control tubes each having two output electrodes and an output circuit connected between said electrodes and including said power supply, a plurality of load relays corresponding in number to said tubes and respectively connected in the different output circuits of the latter in series with one of said electrodes thereof for energization of each relay when the output circuit of the corresponding tube is completed and the tube is conditioned for conduction, each of said relays having normally closed contacts in the output circuits of an end one of said series of tubes and all tubes in the series between such end tube and the tube corresponding to the relay whereby the output circuit of each tube is interrupted by conduction of any of the tubes located between such tube and the other end tube of the series and energization of the associated relay, and selectively operable biasing means in addition to said normally closed relay contacts for conditioning a selected one of said tubes for conduction while the other tubes are biased non-conductively.

4. In control apparatus, the combination of, a power supply, a plurality of load control tubes each having two output electrodes and an output circuit connected between said electrodes and including said power supply, a plurality of load relays corresponding in number to said tubes and respectively connected in the different output circuits of the latter in series with one of said electrodes thereof for energization of each relay when the output circuit of the corresponding tube is completed and the tube is conditioned for conduction, the output circuit of each tube including between the tube and said power supply, normally closed contacts of each of said relays in the output circuits of the other of said tubes disposed between such tube and one end of said series whereby conduction by any tube and energization of the corresponding relay results in interruption of the output circuits of the tubes between the conducting tube and the other end of the series, and selectively operable biasing means in addition to said normally closed contacts for conditioning a selected one of said tubes for conduction while the other tubes are biased non-conductively.

5. In control apparatus, the combination of, a plurality of load control elements arranged in a series and each having an output circuit, a plurality of load devices corresponding in number to said control elements and respectively connected in the different output circuits of the latter for energization of each load device when the corresponding control element is rendered effective, each of said load devices operating when energized to interrupt the output circuits and thereby disable the corresponding load devices of the control element at one end of said series and all of the control elements between such end element and the control element corresponding to the energized load device whereby to avoid actuation of more than one load device simultaneously, and selectively operable biasing means in addition to said load devices for rendering a selected one of said control elements effective while the other elements are biased so as to be ineffective.

6. Control apparatus having, in combination, spaced control and operating stations, a plurality of load control tubes at said operating station arranged in a series and each having first and second control electrodes and adapted to conduct current when both electrodes are at substantially zero potential, first bias control circuits con-

ected to said first electrodes and operable to apply bias potentials of progressively increasing magnitude thereto, second bias control circuits connected to said second electrodes and operable to apply bias potentials of progressively decreasing magnitudes thereto, and a circuit for changing the bias potentials of said electrodes selectively and bringing the potentials of the electrodes of any one of said tubes substantially to zero to condition the tube for conduction while maintaining a cut-off potential on one of the electrodes of each of the other tubes, said circuit including two conductors extending between said stations, two voltage control elements connected respectively to said first and second bias circuits to vary said potentials in the latter in accordance with voltage changes across the elements, a source of voltage connected in series with said elements across said conductors at said operating station, and remote control resistance means at said control station bridging said conductors and selectively adjustable to vary the voltage across said elements.

7. In control apparatus, the combination of, a plurality of load control tubes arranged in a series and each having a cathode and first and second control electrodes, a conductor connected to the cathodes of said tubes, a plurality of first resistors connected in series and respectively connected between adjacent ones of said first electrodes of said tubes in said series, a second resistor connected between said cathode conductor and one terminal of said series of said first resistors to complete a bias circuit between the cathode and the first electrode of each tube, a plurality of third resistors connected in series and respectively connected between adjacent ones of said second electrodes of said tubes, a fourth resistor connected between said cathode conductor and one terminal of said series of third resistors to complete a bias circuit between the cathode and the second electrode of each tube, means including a voltage source connected across each of said series of first and third resistors to apply to said first electrodes potentials of progressively increasing magnitudes with respect to the associated cathodes and to apply to said second electrodes potentials of progressively decreasing magnitudes with respect to the associated cathodes, and a control circuit including said second and fourth resistors and selectively operable electrical means to change the potentials across the second and fourth resistors and correspondingly change the potentials effective on said electrodes of said tubes.

8. Control apparatus having, in combination, a plurality of load control tubes arranged in a series and each having a cathode and first and second control electrodes, a first bias control circuit comprising a direct current source of voltage and a plurality of resistors connected in series across said source and having corresponding terminals connected to the respective first electrodes of said tubes to bias these electrodes at different potentials of progressively increasing magnitude, a second bias control circuit comprising a direct current source of voltage and a plurality of resistors connected in series across the source and having corresponding terminals thereof connected to the respective second electrodes of said tubes to bias these electrodes at potentials of progressively decreasing magnitudes, a conductor connected to said cathodes of said tubes, two resistors, one connected between said cathode conductor and each of said bias circuits at points in the latter between said sources and said resistors thereof to complete bias circuits between the cathode and each of said electrodes of each tube, and a third circuit including means for varying the voltage across said two resistors selectively to increase said decreasing potentials and decrease said increasing potentials to bring the potentials of both electrodes of each of said tubes substantially to zero to condition the tube for conduction.

9. In control apparatus, the combination of, a first grid bias circuit including a voltage divider having a succession of taps of progressively increasing potentials, a second grid bias circuit including a voltage divider having

a succession of taps of progressively decreasing potentials corresponding to the taps of said first divider, a series of electron tubes each having two control electrodes one connected to a tap of said first divider and the other connected to a corresponding tap of opposite potential on said second divider to render the tube conductive when the potentials of both taps are approximately zero and to maintain the tube non-conductive when the potential of each tap is below the grid cut-off potential of the tube, a conductor connected to the cathodes of said tubes, a bias control resistor having a first section connected in series with said first divider between the latter and said conductor and a second section connected in series with said second divider between the latter and said cathode conductor, and a third circuit extending across said control resistor and including adjustable means operable to vary the current flow through the resistor selectively in a direction to increase the potentials of said first divider taps and decrease the potentials of said second divider taps to render said tubes conductive selectively.

10. In control apparatus, the combination of, a plurality of load control tubes arranged in a series and each having first and second control electrodes, a first bias control circuit connected to said first electrodes of said tubes to apply to such electrodes different potentials increasing progressively in magnitude from one end of said series to the other, a second bias control circuit connected to said second electrodes of said tubes to apply to such electrodes different potentials corresponding to the potentials of said first circuit but decreasing progressively in magnitude from said one end of said series to said other end thereof, and a third bias control circuit including an element connected to said first and second circuits and having a potential which is added algebraically to said potentials of the two circuits, and selectively variable means for adjusting the potential of said third control circuit element to increase said decreasing potentials and decrease said increasing potentials to bring the potentials of both electrodes of any one of said tubes substantially to zero and thereby condition the tube for conduction while maintaining a negative cut-off potential on one of the electrodes of all of the other tubes.

11. In control apparatus, the combination of, a plurality of load control tubes arranged in a series and each having first and second control electrodes and adapted to conduct current when the potentials of both electrodes are of substantially the same predetermined value, first bias control means connected to said first electrodes and operable to apply thereto bias potentials of progressively increasing magnitudes larger than said predetermined value, second bias control means connected to said second electrodes and operable to apply thereto bias potentials of progressively decreasing magnitudes larger than said predetermined value, and third bias control means connected to said first and second means to change the potentials applied by the latter to said electrodes, and selectively variable means for adjusting said third bias control means to increase the decreasing potentials while decreasing the increasing potentials by corresponding amounts whereby to bring the potentials of both electrodes of any one tube substantially to said predetermined value and thereby condition the tube for conduction while maintaining a negative cut-off potential on one of the electrodes of all of the other tubes.

12. In control apparatus, the combination of, a series of load control elements each responsive to two different bias potentials and rendered operative when such potentials are of substantially the same predetermined value and inoperative when either potential is of a magnitude higher than the predetermined value, first bias control circuits normally applying to said elements bias potentials having magnitudes larger than said predetermined value to maintain the elements inoperative and increasing progressively from one element to the next in the series, second bias control circuit normally applying to said elements bias potentials having magnitudes larger than said

predetermined value and decreasing progressively from one element to the next in the series, and third bias control circuits connected to said first and second circuits to change the effective bias potentials on said elements, and selectively variable means for adjusting said third bias control circuits to increase the decreasing potentials while decreasing the increasing potentials by corresponding amounts whereby to bring both potentials applied to any one element substantially to said predetermined value and thereby render the element operative while maintaining one of the potentials on each of the other elements higher than the predetermined value to render the other elements inoperative.
